COMBINED WASHING AND DRYING
MACHINE

Walter A. Frantz, Shaker Heights, and John J. McCabe, Cleveland, Ohio, assignors to The Apex Electrical Manufacturing Company, Cleveland, Ohio, a corporation of Ohio

Application May 27, 1932, Serial No. 614,001

10 Claims.

(Cl. 68—15)

This invention relates to combined clothes washing and drying machines, and in particular, washing machines which employ a centrifugal extractor for performing the drying operation.

5 One of the objects of this invention is to provide in a machine of the type disclosed, novel supporting means for the tubs in which the washing and drying operations are performed.

Another object of this invention is to provide 10 in a machine of the type disclosed, a shield formed from a plurality of removable panels for protecting and thermally insulating the washer and extractor tubs.

Another object of this invention is to provide in 15 a machine of the type disclosed, novel means for rinsing, disinfecting and sterilizing the clothes after the washing operation has been performed.

Another object of this invention is to provide 20 in a machine of the type described, a form of agitator and tub bottom construction which is arranged to prevent the clothes from working underneath the base of the agitator.

Another object of this invention is to provide 25 in a washing machine operating mechanism of unitary construction, in which the motor and other operating elements of the mechanism can be assembled and tested as a unit separate from the machine.

Another object of this invention is to provide 30 in a machine of the type disclosed, a simple and compact washer drive mechanism, in which the majority of the operating elements are grouped for movement about a common axis.

Another object of this invention is to provide 35 in a machine of the type disclosed, an improved means for starting and stopping the operation of the dasher or agitator.

Another object of this invention is to provide 40 in a machine of the type disclosed, an improved extractor tub construction in which the rotation of the extractor basket and the flow of liquid therein is made use of in emptying the extractor tub.

Another object of this invention is to provide 45 in a machine of the type disclosed, an improved frame construction.

Another object of this invention is to provide 50 in a machine of the type disclosed, an improved pump and pump drive.

Another object of this invention is to provide 55 in a machine of the type disclosed, an improved

supporting structure for the tubs and the operating elements of the machine.

Another object of this invention is to provide 5 in a machine of the type disclosed, an improved means for handling the liquids used in effecting the washing and rinsing operations.

Another object of this invention is to provide 10 in a machine of the type disclosed, an improved means for securing the caster bearings in position in the supporting legs of the machine.

Another object of this invention is to provide 15 in a machine of the type described, a combined valve and strainer through which water may be supplied to the tubs of the machine.

Another object of this invention is to provide 20 a self-contained multi-chamber washer, having water supply control and directing means and provisions for connecting the machine to a source of hot and cold water supply and to a drain.

A further object of this invention is to provide 25 in a machine of the type disclosed, a generally improved and simplified mechanism embodying a minimum number of parts, which are designed and assembled so as to permit the manufacture of such a machine by modern high speed factory production methods.

With these and other objects in view, the invention consists in the novel construction, arrangement and combination of parts, hereinafter illustrated and described and some of its embodiments in the accompanying drawings, and particularly pointed out in the appended claims.

In the drawings:

Referring to the complete washing machine illustrated in Figure 1, the numeral 1 indicates a washer tub which is provided for the purpose of 45 effecting therein the washing of clothes and other articles. Beside the washer tub, there is positioned an extractor tub 2, in which adherent liquid is separated from the clothes after they have been washed or rinsed. The tubs 1 and 2 50 are preferably formed from steel stampings and finished with a coating of vitreous enamel.

The washing operation is effected by means of an oscillatable dasher or agitator 3, which extends upwardly from the bottom of the washer tub 1, and 55 which is mounted for movement about a vertical axis. The agitator 3, is driven by a motor 4, which is supported beneath the washing compartment 1, and connected in driving relation to the agitator 3, through suitable gearing which will be 60 described in detail presently.

The agitator or dasher 3, operates with a reversely rotary movement about a vertical axis and swings through an arc of substantially one hundred and eighty degrees during its operation. A 65 perforated extractor basket 5, is mounted for rotation in the extractor tub 2, and it is driven by the motor 4, through suitable mechanism which is housed and supported beneath the extractor tub.

The extractor tub 2, and the washer tub 1, are 70 secured in place between a stamped metal base member 6, and a die-cast metal apertured top plate 7. Three supporting legs 8 are secured directly to the base member. The supporting legs are provided with casters 9, to facilitate moving 75 the machine about from place to place.

The extractor and washer tubs are clamped in place in the machine between the top plate 7, and the base 6, by means of the tie rods 10. These rods are rectangular in cross section and are finished with upper and lower threaded ends 11 and 12, 5 respectively. The upper threaded ends 11 of the rods are received in drilled and threaded bosses 13, which are formed integrally with the top plate at spaced intervals on its underside.

The lower threaded ends 12 of the rods project through suitable holes 14, pierced in the base member 6, and they are fitted with nuts 14^a, by means of which the top plate is brought into engagement with the channeled rubber rings 15 and 16, which are fitted over the top edges of the 15 washer and extractor tubs, respectively. A number of rubber pads 17, are interposed between the base 6 and the bottoms of the washer and extractor tubs.

In this manner a strong and resilient mounting is provided for the tubs. The stated tub holding means does not require the piercing of the tubs for bolt holes and the like, thus eliminating the possibility of leakage at such points.

Chipping, cracking and crazing of the porcelain enamel of the tubs during the assembling of the machine or in its subsequent use, is practically eliminated through the expedient of gripping the tubs between a yielding material such as rubber which is in contact with a relatively large area of the tubs. This mounting arrangement avoids the setting up of localized strains in the tubs and thus, eliminates the most common cause of failure of the enamel of the tubs.

The tie rods 10, are drilled and tapped at 18, for the reception of the screws 19, which serve to hold the finishing strips 20, in contact with the vertical edges of the removable panels 21. The lower edges of the panels are fitted with channeled strips of rubber 22, for the sake of appearance and to insure sealing contact with the base 6, of the machine at these points.

The removable panels 21 enhance the appearance of the machine and, at the same time, serve to thermally insulate the washer tub and to protect the tubs against damage. The panels are of sufficient strength to withstand a relatively heavy blow and even though they are damaged by such a blow, the enameled tubs in most cases, will be found to be unharmed and the machine can be 50 easily reconditioned by simply replacing the damaged panel with a new one. This operation is easily performed by first removing the two strips 20, which hold the panel in question, whereupon the panel can be removed and a new one inserted 55 in its place.

A water supply hose 23, connects the machine with hot and cold water supply lines (not shown). The top plate 7, supports a combined valve, strainer and spray nozzle structure 24. The valve and spray nozzle are arranged so that the water supplied by the hose 23, may be controlled and directed into either the washing container 1, or the extractor basket 5.

The machine is provided with a pump 25, 65 which is connected to a drain hose 26, that terminates in a goose-neck 27. The goose-neck is connected to the hose by a swivel coupling 28, and is provided for the purpose of holding the hose in position to discharge into the washer tub 70 or elsewhere as desired. The extractor tub 2, is directly connected to the pump inlet and is continually drained by the pump during the operation of the machine. The draining of the washer tub 2, is under control of a valve 29.

The operation of the agitator 3, is controlled by means of a control lever 30, to which is secured a grip or handle 31. The control lever 30, is capable of occupying three fixed positions. In the 5 first position, the motor 4 is inoperative. In the second position the motor is connected to an electric circuit and placed in operation. In the third position, the washing machine agitator 3 is connected in operated relation with the washing 10 machine gearing and the driving motor.

The top plate 7, is provided with openings 32 and 33, which register with the washer and extractor tubs, respectively. A removable cover 32a is provided for the tub opening 32. A dished 15 cover or chute 34, is pivotally supported in the top plate 7 on a horizontal axis adjacent to the opening 33. The opening and closing of the cover 34 stops and starts the rotation of the extractor basket 5. This control of the extractor basket is 20 accomplished by means of a cam 35, which is integrally formed with the cover, and by other mechanism which will be described in detail in the latter part of this specification.

The arrangement of the extractor control is 25 such that when the extractor cover 34 is in its open position, as shown in Figure 1, the extractor basket 5 is disconnected from its driving mechanism and a brake is applied to prevent its rotation. In the closed position of the extractor 30 cover, the brake is automatically released, and the extractor basket is connected in driven relation with its driving mechanism.

The water and clothes contained in the washer tube are given a vortex movement by the to and 35 fro rotation of the agitator 3, and in this manner the clothes are quickly and effectively washed.

The agitator 3, is provided with three vertical vanes 36, which extend upwardly from a frusto-conical base plate 37. The vanes of the agitator 40 are extended beyond the margin of the base plate 37 for the purpose of preventing the clothes from getting underneath the downwardly turned edge 38 of the base plate.

45 As a further means for preventing the clothes from getting underneath the edge 38 of the base plate, the tub is provided with a conical raised portion 39, which extends upwardly into the conical base of the agitator. The downwardly turned edge 38, of the agitator base closely approaches the conical upraised portion 39 of the tub bottom, at a point some distance above the point where this part of the tub merges into the horizontally disposed portion 40, of the tub bottom. 55

As previously stated, the operation of the agitator induces a vortex movement of the contents of the tub. The relative movement of the water and clothes, with reference to the central portion 60 of the tub bottom, is outwardly and upwardly and then inwardly and downwardly.

The contour of the agitator base and the exposed area of the upraised portion of the tub bottom conforms at this point, approximately to 65 the flow lines of the moving contents of the tub when the machine is in operation. This arrangement permits better circulation of the tub contents with a smaller power consumption than would be possible with the use of an agitator base, the shape of which tended to oppose the 70 flow of the tub contents or which varied greatly from the flow lines of the moving contents of the tub.

The natural counter-flow induced at the outermost edges 41, of the trailing face of the vanes 36,

is not sufficient to throw the clothes against the marginal edge of the agitator base on account of the relatively great distance between these points, and in the normal operation of the machine, the movement of the clothes is always in a direction 5 away from such a point.

Under abnormal conditions, such as when the machine is loaded with an excessive amount of clothes, the extended portions 41 of the vanes operate to sweep the clothes clear of the line 10 where the agitator base approaches the tub bottom.

The agitator 3, is removably secured to its operating shaft 42, by means of an elongated bolt 43. The end 44, of the agitator shaft, is prismatic 15 in shape and has a plurality of flat sides which taper towards the axis of the shaft. The agitator base is provided with a central socket 45 of complementary form to the prismatic end 44 of the shaft, for receiving this end of the agitator 20 shaft. This arrangement provides a detachable driving connection between the shaft 42 and the agitator 3. The end of the shaft 42 is internally threaded for receiving the bolt 43, by means of which the agitator is securely held in place on its 25 shaft.

The washer mechanism gearing of the machine is confined within a two-part gear case, the base 46 of which is used to support the motor 4. The mechanism in the gear case is driven by 30 the motor 4, by means of a V belt 47, which engages the motor pulley 48, and the mechanism pulley 49.

A centrifugal clutch 50, which is formed in part by the motor pulley 48, is provided to permit the motor to come up to speed before the load of driving the washing machine mechanism is imposed upon it. The clutch 50 is of similar construction to the clutch illustrated in copending U. S. patent application Serial Number 497,678, which was filed by W. A. Frantz and A. W. Seyfried, November 24, 1930, and issued as Patent No. 1,983,661 on December 11, 1934.

In the form of clutch just referred to, a centrifugally operated clutch member 51 is fixedly connected to the motor shaft 52. A clutch drum 53, is integrally formed with the pulley 48. The drum and pulley are rotatably journaled on the motor shaft and when the motor comes up to speed, the centrifugally operated part 51 of the clutch, frictionally engages the drum 53, and drives the pulley at the same speed as that of the motor shaft. If an overload is imposed upon the motor, the clutch immediately begins to slip, and thus prevents any damage to the motor. 55

The motor 4 is secured to the gear case base 46, by means of a pair of stamped metal plates 54 and 55. These plates are formed with complementary channels 56 and 57, respectively, between which there is received a rubber sleeve 58 60 and a supporting shaft 59 which it incloses. The motor 4 is pivotally suspended from the projecting ears 60 of the gear case, which are apertured for receiving the uncovered ends of the shaft 59. The stamped metal motor supporting members 65 54 and 55 are secured to the motor and each other by means of a pair of bolts 61.

The lower supporting plate 55 is provided with an extending arm 62, which is engaged between the spring 63 and a wing nut 64. The spring 63 70 is compressed between the arm 62 and the gear case base 46 and it serves to resiliently hold the arm 62 in contact with the wing nut 64. The wing nut is threaded onto a rod 65, the upper end of which is screwed into a boss 66, formed on the 75

base 46 of the gear case. The boss 66 also serves to position and guide the spring 63, which surrounds it.

A pair of dielectric washers 67 and 68, are 5 provided to insulate the arm 62 from the spring 63 and the nut 64. The upper washer 67 is engaged by the spring 63 and the lower washer 68 is engaged by the wing nut. The provision of the washers just mentioned, and the rubber sleeve 58, 10 which forms a sheath for the shaft 59, serves to electrically insulate the motor 4 from the rest of the machine. The sleeve 58 has flanged ends 69, for preventing contact between the plates 54 and 55 and the ears 60. The arm 62 is slotted or 15 forked at 70, for receiving the rod 65.

The spring 63 is arranged to resiliently oppose the pull of the belt 47 and it co-operates with the rubber sleeve 58 to provide a resilient and flexible mounting for the motor 4. By this arrangement the motor noises are not transmitted to and amplified by the rest of the machine and an extreme degree of quietness in operation is attained by reason of such construction.

The lower half or base 46 of the gear case, 25 may be constructed in the form of a metal casting. The mechanism belt pulley 49 is fixedly connected to a worm shaft 71, which is journaled at one end in an anti-friction bearing 72. An oil seal 73 is provided between the shaft 74 and, 30 the gear case to prevent the escape of oil at this point. The opposite end of the worm shaft is journaled in a plain bearing 74, formed in the gear case base. An oil seal 75 is also provided in the end of this bearing to prevent the escape 35 of oil from the gear case. A worm 76 is threadably secured to the shaft 71.

The lower end of the agitator shaft 42 is journaled in a bearing 77, which is formed in the boss 66 of the gear case base. The shaft 42 provides a bearing for the worm gear 78, which meshes with the worm 76. An eccentric 79, having a hole adjacent to its marginal edge for the receiving of the bushing 80, is fixedly secured to the top of the worm gear 78 by means of the bolt 81, which is screwed into the gear 78.

A connecting rod or pitman 82, receives the eccentric 79 in a suitable bearing 83, formed in one of its ends. The rod 82 is held in place on the eccentric by means of a plate 84, which is fitted over the top of the eccentric and which extends beyond the edge of the eccentric to cover the bearing portion 83 of the connecting rod. The plate 84 is held in position by means of a plurality of drive screws 85, which are driven in the drilled holes 86 of the eccentric.

The opposite end of the connecting rod 82 is provided with a hole 87, in which a bearing pin 88 is riveted. The pin 88 is journaled in a bearing 89, which is formed in the segmental gear 90. The pin is held in place in the gear 90, by means of a plate 91, which is secured to the pin 88 by the drive screw 92. The segmental gear 90 is journaled on a laterally movable bearing pin 93. The rectangular base 94 of the bearing 93 is received in a channel member 95, which is fixedly secured to the gear case base by means of drive screws 96.

The lateral movement of the bearing member 70 93 is effected by means of a pinion 97 which meshes with the rack teeth 98 formed in the axial opening 99, which is provided through the bearing member 93. The pinion 97 is in the form of an elongated mutilated gear having 75 a sufficient number of teeth 100, formed thereon,

to shift the bearing member a slight distance back and forth in its guideway 95.

The pinion 97, is provided with an enlarged cylindrical lower end 101, which is journaled in a suitable bearing 102, formed in the base of the gear case. The gear segment 90 is provided with gear teeth 103 which engage with the gear teeth 104, which is fixedly secured to the agitator shaft 42, by means of a key 105.

From the foregoing it is apparent that during 10 the time of operation of the motor 4, the worm 16, the worm gear 78 and the eccentric 79 are continuously driven, the latter two elements being rotated about the agitator shaft 42, as a bearing pin. At the same time, the connecting rod 15 82 swings the gear segment 90 back and forth about its supporting shaft 93, and this movement of the segment is transmitted through the pinion 104 to the agitator shaft 42, giving it a reversely rotary angular movement of substantially one 20 hundred and eighty degrees in each direction. It is understood, of course, that such movement of the agitator shaft takes place only when the gear segment 90 is in mesh with the agitator shaft 25 pinion.

The driving of the agitator shaft may be controlled at will by simply rotating in one direction or the other, the pinion 97, which controls the position of the segmental gear bearing pin 93. The agitator shaft 42 provides a bearing member for the worm gear 78 and its associated eccentric 79, thus permitting a very compact arrangement of the elements of such a mechanism while, at the same time, eliminating several parts, such as the worm gear supporting shaft and its 30 associated bearings, which are customarily employed in such mechanisms.

The upper end of the segmental gear shifting pinion 97, is received in a central opening of complementary form, provided by the segmental pinion 106. The segmental pinion 106, is securely held in place on the pinion 97 by means of the bolt 107 and washer 108, the former of which screws into the pinion 97. The segmental pinion 106, is operatively geared to a shifting quadrant 109. This quadrant has gear teeth 110, which mesh with the gear teeth of the pinion 106.

The quadrant 109, is rotatably supported about the agitator shaft bearing member 111, and is held in position thereat by means of the plates 50 112, and their retaining bolts 113, which also serve to hold the bearing member in place on the gear case cover 114. The shifting quadrant has an integrally formed arm 115, to which the shifting lever 30 is secured by means of the bolts 55 116.

The gear case cover 114 may be formed from a metal stamping with suitable openings for the agitator shaft bearing 111, and the segment shifting pinion 97. An annular bearing 117 is pressed 60 out of the gear case cover for receiving and providing a bearing for the depending sleeve 118 of the segmental pinion 106. This pinion is also provided with a downwardly turned outer edge 119, which is provided for the purpose of retaining the packing ring 120 in place. The packing ring 120, is provided to prevent the escape of oil from the gear case at the bearing 117.

The gear case cover is formed with an outwardly turned edge 121 for engaging the correspondingly formed top edge 122 of the cast metal base of the gear case. A plurality of bolts 123, are used to secure the upper and lower portions of the gear case to each other. The central opening 124, provided in the gear case cover for the 75

agitator shaft 42, has an annular ring 125, welded thereabout to the under side of the gear case cover. The ring 125 is provided to strengthen and thicken the gear case cover at this point so that it may be drilled and tapped for receiving the bolts 113 provided to hold the bearing member 111 in place on the gear case cover.

The agitator shaft bearing 111, extends a slight distance above the gear case cover and is provided at its top with an annular shoulder 126, which engages centrally with the underside of the tub bottom. An exteriorly threaded cup 127, is screwed into the bearing member 111. When in place, the upper end of this cup extends above the top of the bearing member and projects into the tub 1, for a short distance. A lock nut 128, is screwed on the end of the cup to clamp the central portion of the tub bottom to the bearing member 111. Suitable gaskets or washers 129 are provided between the tub and the bearing member and lock nut, to make a leak-tight joint at this point.

The interior of the cup 127 is of somewhat larger diameter than the shaft 42, for the purpose of accommodating the packing material 130. Beneath the packing material, a packing gland 131 is loosely fitted in the cup. A spiral spring 132 engages the gland 131 and pushes it against the packing material 130. In this manner the packing material is automatically maintained in adjustment and it serves to provide a fluid-tight seal for the shaft 42 over an extended period of time.

Should it ever be necessary to renew the packing material the cup 127 can be readily removed through the tub bottom for this purpose, without disturbing the rest of the machine.

A passageway 133 provides communication between the packing cell of the cup 127 and the interior of the gear case for the purpose of returning to the gear case the oil that works its way up the agitator shaft bearing and which would have a tendency to force its way through the packing and there escape into the washer-tub if it were not for the provision of the drain hole provided by the passageway 133.

The gear shifting pinion 106 and quadrant 108 and the agitator shaft bearing 111 may be constructed of die castings to eliminate a large number of machining and other finishing operations on such parts. The bearing pin 93 for the gear segment 90 also may be constructed of a die casting.

A spiral groove 134 is formed on a portion of that part of the worm shaft 71 which is received in the bearing 74. One end of the spiral groove 134 is in contact with the oil in the gear case and during the rotation of the shaft, the spiral groove causes oil to be forced into the annular groove 135 which is cut in the shaft at the opposite end of the spiral groove. The bearing 74 is drilled at a point opposite to the annular groove 135 for the reception of the oil pipe 136. This pipe communicates with the annular groove 135 and conducts oil therefrom to the top surface of the segmental gear 90.

The web 137 of the gear 90 is located on a lower level than the edges of the gear segment and thus provides a shallow open container which is capable of holding considerable amount of lubricant. Oil holes 138 are drilled in the gear segment for supplying oil to the bearing surfaces of the pins 88 and 93 and to the gear teeth of the agitator shaft pinion 104.

In this manner a combined gravity and force-

feed lubrication system is provided for the working parts of the machine and a very small amount of oil in the gear case will effectively lubricate all of the mechanism in the gear case. The outer end of the worm shaft has a shallow spiral groove 134 cut in its surface to prevent the escape of oil from the gear case. The groove 134 runs oppositely to the groove 134 and during the rotation of the shaft 71 it tends to force oil in a direction to the left along the shaft as viewed in Figure 26.

The worm shaft 71 extends through the gear case at the bearing 74 and is there connected to a horizontal drive shaft 139 by means of a universal joint 140. The universal joint is provided with a cover 141 for retaining a supply of grease about the joint. The opposite end of the drive shaft 139 is connected by means of a similar universal joint 142 to the stub shaft 143. This joint is also provided with a dirt excluding and grease retaining cover 144.

A spring 145 is carried in one end of the connecting shaft 139 to take up the end play and prevent the vibration of the shaft when it operates. A channel or trough-shaped guard 146 is supported beneath the shaft 139. This guard extends a distance beyond the ends of the shaft and serves to catch the oil that might escape from the bearings beneath which it is positioned, as well as providing a guard for the shaft 139.

The shaft 143 is journaled in the bearings 147 and 148 of the extractor gear case base 149. The shaft 143 is provided with a helical gear 150 which is rigidly fixed thereon at a point intermediate the ends of the shaft. An oil seal 151 prevents the escape of oil from about the bearing 147. The helical gear 150 engages a second helical gear 152, mounted for rotation about a vertical axis. A third helical gear 153, carried by the horizontal pump shaft 154 meshes with the last mentioned helical gear 152 for the purpose of driving the pump 25. A ball thrust bearing 148 is provided for the shaft 143.

An extractor basket supporting shaft 155 is mounted at its lower end in an anti-friction bearing 156. This bearing is fitted in a suitable opening 157 provided in the bottom half 149 of the extractor gear case. A closure cap 158 secures the bearing in place in the gear case base. The extractor shaft 155 is provided with a threaded lower end for reception of a lock nut 159, by means of which the shaft 155 is secured to the cone 160 of the anti-friction bearing whereby the shaft is held against axial movement.

The gear case for the extractor mechanism is formed with lower and upper halves 149 and 161, respectively. The lower half of the gear case or base 149, is formed with bearings for the motor driven shaft 143 and the control shaft 197. The cover or upper half 161 of the extractor gear case is formed with a central opening 162, for reception of the extractor shaft upper bearing 163.

The extractor shaft bearing 163 is exteriorly threaded at 164 and is provided with an outwardly extending flange 165, at its lower end. A nut 166, engaging the threaded part 164 of the bearing 163, is provided for securing the extractor gear case to the frame of the machine and to the extractor tub. Suitable gaskets 167 are provided to prevent leakage of water about the central opening 168 of the extractor tub through which the bearing 163 projects.

The extractor shaft is provided with a frusto-conical upper end 169, which is received in the frusto-conical socket 170 of the extractor basket base 171. The extractor basket 5 may be readily removed from the shaft 155 by reason of the form of coupling used which constitutes a detachable frictional driving connection.

The extractor basket base 171 is in the form of a bell-shaped die casting. An inwardly tapering sheet metal drum 172 is secured to the base 171 by the rivets 173. The taper of the shaft end 169 is such that the weight of the basket is sufficient to provide for a good frictional driving connection at this point, while at the same time, permitting a slight amount of slippage in starting and stopping the rotation of the basket.

Perforations 174 are formed in the side walls of the basket to permit the expelling of water from the basket during its operation. The base portion of the extractor basket is provided with a plurality of holes 175, to permit the drainage of water from this portion of the basket. The upper end of the extractor basket carries an annular ring 176, which is provided to prevent clothes from dropping between the extractor basket and its tub 2. This ring may be of stamped metal construction and is pressed into position on the top of the extractor basket.

A shaft seal is provided at the upper end of the extractor shaft bearing to prevent the ingress of water into the extractor gear case and to prevent the escape of oil from such gear case to the extractor tub. This seal is formed from a metallic bellows 177, which is sealed and secured at its upper end to the extractor shaft. The lower end of the bellows is fitted with a sealing ring 178, which frictionally engages the smoothly finished end 179 of the extractor shaft bearing 163. The bellows 177 is slightly compressed so that its natural resiliency will urge the ring 178 into sealing contact with the end 179 of the bearing 163.

The helical gear 152 is fixedly secured to a clutch member 180, which is freely journaled on the extractor shaft 155. At its upper end the clutch member 180 is provided with a conical clutch face 181. The member 180 is held against axial movement by the shaft shoulder 182 and the collar 183.

Co-operating with the clutch member 180, which is connected to the spiral gear 152, there is provided a second clutch member 184, which has a lower conical clutch face 185, provided for co-operation with the clutch face 181 of the aforesaid member. The clutch member 184 is slotted at 186, for receiving the shaft key 187. In this manner the member 184 is mounted for rotation with the shaft and for axially slideable movement thereon.

A spring 188 is compressed between the top of the clutch member 184 and the washer 189, which is held in position on the shaft 155 by means of the pin 190. The upper end of the vertically slideable clutch member 184 is formed with a frusto-conical brake face 191, which engages a brake member 192 having a brake face 193 of similar contour. The brake member 192 is provided with a pair of radially extending arms 194, which are provided for engagement by the fingers 195, of the clutch shifting fork 196. The brake member 192 has a pair of vertically channeled guideways 192^b for receiving the guides 192^b to prevent the rotation of the member 192.

The shifting fork 196 is fixedly secured to the rod 197, by means of a set screw 198. The rod is journaled in a bearing 199, which is formed in the gear case base 149 and at its outer end it is provided with a crank arm 200. An oil seal 201 is fitted in the outer end of the bearing 199, to prevent the escape of oil from the gear case at this point. The crank arm 200 is rigidly secured to the end of the rod and held thereon by means of the nut 202. The crank arm 200 is engaged by the lower end of a rod 203, which is operated by means of the cam 35, provided by the extractor cover 34. Contact is maintained between the rod 203 and the cam 35 and arm 200, by means of the tension spring 204, which is secured at its ends to the crank 200 and the washing machine base 6.

The lower end of the rod 203 is threaded for the reception of the bolt 205, by means of which its length can be readily adjusted. A lock nut 206 is provided for the bolt 205. The head of the bolt 205 is received in a shallow cup 207, which is formed in the end of the crank arm 200. The washing machine top plate 7 has an apertured arm 208 integrally formed therewith for receiving and guiding the upper end of the rod 203. The lower end of the rod 203 is guided in a bracket which is carried by the machine base 6.

During the operation of the motor 4, with the parts in the position they occupy in Figure 1, the extractor basket will be at rest with the braking surfaces 191 and 193 in contact with each other. To start the rotation of the basket 5, it is only necessary to close the lid 34, whereupon the movement of the cam 35 allows the rod 203 and the crank arm 200 to rise under influence of the spring 204.

The movement of the crank arm 200 is transmitted to the shaft or rod 197, and its associated shifting fork 196, which is thereby moved downwardly, lowering the brake member 192 out of contact with the brake surface 191, of the combined clutch and brake member 184. Coincidentally with this operation, the spring 188 moves the clutch member downwardly, bringing the frictional clutch faces 181 and 185 into engagement, whereupon the basket 5 is driven by the rotating member 180.

The stopping of the extractor is accomplished by opening the lid 34. This operation moves the aforesaid extractor control elements in a manner reverse to that just explained, to separate the clutch surfaces 181 and 185 and to bring the braking surfaces 191 and 193 into engagement whereby the basket is quickly brought to rest.

The pump 11 is of the impeller type and it comprises a pump case 210 and a pump cover 211, which inclose a bladed impeller 212. The pump case 210 has an extended portion in which is formed a bearing 213 and a packing chamber through which the pump shaft 154 extends. The pump case is secured to the extractor gear case base 149 by means of the screws 214.

The packing chamber of the pump case is arranged to receive in the order named, a spiral spring 215, a loosely fitted packing gland 216, the packing material 217 and a gland nut 218. The packing gland 216 is loosely fitted in the packing chamber so that it is free to be moved by the spiral spring 215, to force the packing material 217 into sealing relation with the pump shaft 154. The extended portion of the pump case projects into the interior of the extractor gear case and the pump shaft by reason of this

arrangement, is lubricated by the oil carried in the extractor gear case.

The end of the pump shaft is threaded at 219, for receiving the bladed impeller 212 of the pump.

5 The pump cover 211 is provided with a central inlet opening 220, which communicates with two branched conduits 221 and 222. The branch 221 connects with the valve 29 and the branch 222 connects with a fitting provided in the bottom 10 of the extractor tub.

These connections are made by means of flexible hose couplings 223 and 224, respectively, which are suitably secured at their ends to the branches 221 and 222, and to the aforesaid parts. The fitting connecting the pump with the extractor tub, 15 comprises an internally threaded flanged coupling 225, which is engaged by an externally threaded flanged screen member 226. Gaskets 227 are engaged between the flanges of the fitting parts 20 and the extractor tub, to make a tight joint at this point.

The bottom portion of the extractor tub is formed with a trough-like depression 228, so that the fitting just mentioned, enters the tub tangentially and on an angle of about forty-five degrees with the horizontal. By this arrangement the rotation of the basket tends to force the liquid in the tub out through the stated drain opening provided for carrying away the water 30 in the extractor tub. The natural movement of the water in the extractor tub is in a direction so that it tends to escape from the extractor tub by way of the stated drain opening.

35 The pump cover 211 forms a trap for solid materials. The trap is fitted with a removable screen 229, which is held in position by means of the removable closure cap 230. The screen is located in the cover between the pump inlet and the conduits communicating with the tub drain 40 openings and it serves to prevent small articles of clothing and other materials from getting into the pump case.

The draining of water from the washer compartment is under control of the valve 29. This 45 valve is of the plug type and its plug is connected for rotational movement by a control handle 231. For the position of the handle as shown in Figure 1, the valve is in its open position and when the handle is turned about ninety degrees in a 50 counter-clockwise direction, the valve is closed. The pump case is of snail-shape construction and has a tangential outlet 232, on its periphery for connection with the drain hose 26.

55 The top plate 7 is formed with an opening 233, for receiving the goose-neck 27, of the drain hose. As best shown in Figure 7, this hole terminates in a curved lip 234, which acts as a sort of a guard or trap to prevent water escaping from the tub when the agitator is working and when 60 the goose-neck is not in the hole.

The base 6 of the machine is formed from a steel stamping and it is provided with a centrally depressed portion 235, for the purpose of strengthening and stiffening it. The base is provided at its outer edge with a downwardly extending skirted portion 236.

65 The lower web portion 235 of the base 6 is provided with separate apertures for receiving the washer driving mechanism gear case and the 70 extractor driving mechanism gear case. The base 6, as is best shown in Figures 16 to 19, is formed with a flanged marginal portion or skirt 236 and horizontal, vertically offset web portions and interconnecting stiffening web portions. The 75 washer and extractor tubs are supported from

the upper horizontal portion and the gear cases are mounted in the lower horizontal portion of the base. The base 6 has a sinuous cross-sectional outline, as is shown in sectional views Figures 17 to 19.

5 By reason of this construction, a very rigid, yet light weight base is provided. The base is further strengthened by means of a plate 237, which is welded and riveted to the top of the base. This plate is located adjacent to the end of the base 10 on which the extractor is supported.

A plurality of threaded nuts 238, 239 and 240 are riveted to the base for the purpose of receiving the bolts which are used to secure the washer gear case, the extractor gear case and the legs 15 of the machine to the base. In forming the aforesaid nuts, they are provided with an annular reduced section adapted to closely fit within and project through the holes provided in the base for their reception. The projecting annular portion of the nuts, as illustrated best in Figure 20, 20 is then curled or peaned over the plate of the base to securely and rigidly fix the nuts in position thereon.

The lower half or the base 46, of the agitator 25 driving mechanism gear case, is provided with three ears 241 upon which are formed the pads 242. These pads or bosses are ground level with the top edge 122 of the gear case and are drilled at 243 for the reception of the bolts by means of 30 which the gear case is secured to three nuts 238 which are carried by the stamped metal base 6.

In a like manner, the lower half 149, of the 35 extractor gear case is provided with three ears 244, upon the upper surface of which are formed the pads or bosses 245. The pads are ground level with the top of this part of the gear case and are drilled at 246, for receiving the bolts which engage the nuts 239, to secure the gear case to the base 6.

40 The ends of the nuts 238 and 239 are all ground, preferably with a surface grinder, so as to be on the same level and on a predetermined distance from the top of the base member 6. The portions of the gear cases which engage these 45 nuts are also ground surfaces so that by reason of this construction, great accuracy and uniformity can be maintained in the manufacture of this machine. The ground upper face of the gear case bases 46 and 149 is used as a reference surface in performing the machining operation on these cases. Where such extreme 50 accuracy is not required, the grinding of the ends of the nuts may be dispensed with as the nuts are machined elements and do not vary 55 greatly in length so that when attached to the base their ends remote therefrom would ordinarily all lie substantially within the same plane.

The skirt 236 of the base is pierced at 244 for receiving the leg securing rivets 245 one of which 60 is provided for each of the legs. The legs 8 are of stamped metal construction.

The top of the legs rest against the underside 65 of the riveted nuts 240 and they are secured to the base at these points by suitable bolts which are received by the nuts 240. The leg rivets and leg bolts serve principally to hold the legs in position and do not carry any substantial part of the weight of the machine; and for this reason they are not apt to become loosened in the use 70 of the machine.

The sturdy construction of the legs of an extractor type washing machine is a very important detail for the reason that such machines are ordinarily subjected to considerable vibration and 75

it is essential that the legs be secured to the machine in such a manner that the operation of the machine will not tend to loosen them.

The vertical pin 246 of the caster 9, is carried in a bearing member 247, which is received in the lower end of the legs. The bearing member 247 is held in position by crimping the edge portions 248 of the legs into a depression 249 formed in the bearing member 247, thus providing a strong and inexpensive form of securing for the caster bearing.

The motor 4 is controlled by a toggle switch 250, having an operating finger 251, under control of an upstanding plate 252, which is carried by the operating lever 30. The switch 250 is operated by a spring (not shown) in one direction and by the plate 252 in the opposite direction; thus, when the lever is shifted to the left, as viewed in Figure 5, the switch closes and starts the motor, and when the lever is shifted to the right, the plate 252 engages the finger 251 to open the switch.

The operating lever 30 works in a slot 253, provided by the plate 254, which is secured by the bolts 254a in position over the slot 255, and which is formed in the skirt 236 of the base. The plate 254 is laterally adjustable for adjusting the position of the lever 30, when the stops 256 and 257 of the quadrant 109 and segmental pinion 106 have been adjusted or filed down, to compensate for wear between the agitator shaft pinion 104 and its driving segment 90. The plate 254 is provided with three notches 258, 259 and 260, formed in one side of the slot 253, for locking the operating lever 30 in its off position, motor operating position and washing position, respectively.

A water supply conduit 23 is connected by means of a coupling 261, to the portion of the L shaped fitting 262, which extends from the side of the machine. The fitting 262 is connected at its opposite end to the top plate 7 of the machine, by means of a lock nut 263, which engages with the threaded portion 264 of the fitting, whereby to secure it in place on the top plate 7. The lock nut 263 also serves to hold a sleeve 265 in position in the fitting 262.

The sleeve 265 is of tapered construction and has a pair of spaced ports or openings 266 and 267, for communication with the fitting 262. A hollow tapered valve plug 268 is journaled in the member 265. The plug has a port 269, which can be brought into registry with either of the ports of the member 265, and thus provide for fluid flow through the valve. The plug 268 is held in sealing relation with the member 265, by means of a nut 270 and washer 271, which are secured to the threaded end portion 272 of the plug.

An integrally formed nozzle 273 and operating handle 274 are fixedly secured to the plug member 268, by means of a threaded rod 275 and a cooperating wing nut 276. The rod is in threaded engagement with the lower end of the plug 268, while the wing nut engages the upper threaded end of such rod. A glass cover 277 is interposed between the wing nut 276 and the inlet end of the nozzle. A filter or screen 278 is held in place by the cover 277 over the inlet opening of the nozzle 273, for the purpose of preventing solid particles of dirt and foreign material from passing through the nozzle 273 and staining the clothes. The screen 278 also serves to hold the water soluble pellets 279, which are formed from a suitable disinfecting material, and

which are used to sterilize the clothes in the extractor basket.

In Figure 4, the spin-rinse valve parts are shown in the position they occupy when water is being discharged into the washer tub. The cover 34 is mounted and arranged so that when it occupies its closed position, its underface is spaced above the top plate 7 a sufficient distance to permit the nozzle 273 to be moved under the cover. When the handle is rotated so as to bring the nozzle under the extractor cover 34 as indicated in dotted lines in Figure 1, the valve plug port 269 registers with the small port 266 of the sleeve 265, and a limited flow of water is discharged into the extractor tub for the purpose of rinsing and sterilizing the clothes contained therein, during the rotation of the extractor basket. The amount of water discharged into the extractor during the spin rinse operation is limited by the size of the valve port 266, so as to be slightly less than the maximum flow, the pump 25 is able to handle. In directing the nozzle 273 to either of the compartments of the machine, the port 269 is brought into registry with one or the other of the ports 266 or 267. When the end of the nozzle 273 overlies the portion of the top plate 7, which separates its openings 32 and 33, the valve ports are in a closed position and no water flows through the nozzle 273.

The spin-rinsing device just described makes it possible to perform all of the customary washing and rinsing operations on the clothes without removing the clothes from the machine. In addition to these advantages, the spin-rinse device permits the use of scalding hot water and disinfectants to sterilize the clothes.

Furthermore it is to be understood that the particular forms of apparatus shown and described, and the particular procedure set forth are presented for purposes of explanation and that various modifications of said apparatus and procedure can be made without departing from our invention as described in the appended claims.

The following list of applications for United States Letters Patent filed by us on the dates indicated, relate to subject matter of invention common to that disclosed but not specifically claimed herein:

Details relating to centrifugal extractor and its operating mechanism, covered by our application, Serial No. 656,404, filed May 13, 1933, for Laundry machine, and issued as Patent No. 2,087,571 on July 20, 1937;

Details of an operating mechanism for an agitator, covered by our application, Serial No. 684,202, filed August 8, 1933 for Clothes washer mechanism, and issued as Patent No. 2,046,258 on June 30, 1936;

Details of a liquid supply means for a laundry machine, covered by our application, Serial No. 684,203, filed August 8, 1933 for Liquid supply and control device;

Details and means for handling and pumping the liquid used in a laundry machine, covered by our application, Serial No. 684,205, filed August 8, 1933 for Liquid handling device;

Details of an agitator drive gearing, covered by our application, Serial No. 702,020, filed December 12, 1933 for Laundry machine mechanism, issued November 5, 1935, Patent No. 2,019,564.

Having thus described our invention, what we claim is:

1. In a laundry machine, in combination, a

5 casing structure having compartments located side by side, an elongated supporting base of unitary construction for carrying said casing structure, operating mechanism carried by said base, laundering means in the compartments of said casing structure operatively connected to said mechanism, said base being formed from sheet metal and having horizontal, vertically offset portions and angularly disposed interconnecting stiffening web portions whereby a rigid light-weight base is provided, and a gear case 10 for said operating mechanism supported in an aperture formed in the lowermost offset portion of said base.

15 2. In a laundry machine, in combination, a casing structure having compartments located side by side, a supporting base for carrying said casing structure, operating mechanism carried by said base, laundering means in the compartments 20 of said casing structure operatively connected to said mechanism, said base being formed from sheet metal and having horizontal, vertically offset portions and angularly disposed interconnecting portions including a downwardly depending marginal skirt portion conforming to the marginal outline of said casing structure whereby a rigid light-weight base is provided, and a gear case for said operating mechanism supported in an aperture formed in the lowermost offset portion of said base.

25 3. In a portable laundry machine, a casing defining a pair of compartments located side by side and having top working openings, covers for said openings, a support for said casing, means 30 for conveying liquid from the bottom of one compartment to the top of the other, and controllable means carried by and forming a part of the machine for discharging fresh water into one of said compartments.

40 4. In a laundry machine, a casing, a reinforcing and supporting base for said casing comprising a sheet metal plate having a marginal portion adapted to engage the casing bottom in supporting relation and having a web defining an aperture in the plate, said web and said marginal portion being of sinuous cross-sectional outline to increase the rigidity of the plate and having holes near said aperture, operating means for the machine including a gear case received within the aperture of said base having bosses with apertures which register with the holes of said plate, and means including members passing through such base holes and gear case apertures for securing said gear case to said plate.

45 5. In a laundry machine, in combination, a casing structure defining a pair of compartments arranged side by side, an elongated, horizontally disposed sheet metal supporting base therefor, means for securing said casing structure in supported relation upon said base, laundering means in the compartments of said casing structure, interconnected mechanisms for operating said laundering means, a pair of gear cases for housing said mechanisms having machined, plane surfaces facing said supporting plate, and means for securing said gear cases to said base including machined members fixedly secured to said base and interposed between and in contact with 50 said base and the machined surfaces of said gear cases, three of such members being associated

with each of said gear cases to define three-point suspensions therefor, the ends of such members all lying in a common horizontal plane.

5 6. In a laundry machine, in combination, a casing structure defining a pair of compartments arranged side by side, an elongated, horizontally disposed sheet metal supporting base therefor, means for securing said casing structure in supported relation upon said base, laundering means in the compartments of said casing structure, 10 interconnected mechanisms for operating said laundering means, a pair of gear cases for housing said mechanisms having machined, plane surfaces facing said supporting plate, and means for securing said gear cases to said base including machined members fixedly carried by and projecting from said base with their ends lying in a common horizontal plane and engaging with the machined surfaces of said gear cases.

15 7. In a laundry machine, a receptacle, a rigid supporting base for said receptacle comprising a sheet metal plate of sinuous cross-sectional outline having a marginal portion upon which the bottom of said receptacle rests in supported relation, said plate also having an offset web defining an aperture in the plate, operating means for the machine including a gear case received within the aperture of said base, and means for securing said gear case to said base.

20 8. In a laundry machine, a receptacle, a rigid supporting base for said receptacle comprising a sheet metal plate of sinuous cross-sectional outline having a top marginal portion upon which the bottom of said receptacle rests in supported relation, said plate also having a web located 25 on a level a substantial distance below the top marginal portion and defining an aperture in the plate, operating means for the machine including a gear case received within the aperture of said base, and means for securing said gear case to said base.

25 9. In a laundry machine, a receptacle, a rigid supporting base for said receptacle comprising a sheet metal plate of sinuous cross-sectional outline having a marginal portion upon which the 30 bottom of said receptacle rests in supported relation, said plate also having an offset web defining an aperture in the plate, resilient cushioning means interposed between the marginal portion of said plate and the bottom of said receptacle, operating means for the machine including a gear case received within the aperture of said base, and means for securing said gear case to said base.

35 10. In a laundry machine, a receptacle, a rigid supporting base for said receptacle comprising a sheet metal plate of sinuous cross-sectional outline having a marginal portion upon which the bottom of said receptacle rests in supported relation, said plate also having an offset web defining an aperture in the plate, resilient cushioning means interposed between the marginal portion of said plate and the bottom of said receptacle, fastening means including a resilient element in contact with said receptacle for securing the receptacle to said base, operating means for the machine including a gear case received within the aperture of said base, and means for securing said gear case to said base.

CERTIFICATE OF CORRECTION.

Patent No. 2,099,163.

November 16, 1937.

WALTER A. FRANTZ, ET AL.

It is hereby certified that error appears in the printed specification of the above numbered patent requiring correction as follows: Page 3, first column, line 34, for the word "tube" read tub; page 7, second column, line 28, strike out "or bosses" and insert the same after the word "pads" in line 27; page 9, first column, line 10, claim 1, strike out the words "stiffening web"; and that the said Letters Patent should be read with this correction therein that the same may conform to the record of the case in the Patent Office.

Signed and sealed this 1st day of February, A. D. 1938.

Henry Van Arsdale,
Acting Commissioner of Patents.
